(57) **ABSTRACT**

A moving direction of an operating member (11) from an initial position toward a connection position with respect to a housing (10) is selectable from directions along a first movement path and a second movement path opposite to each other. The housing (10) includes a first lock portion (25) and a second lock portion (26) at positions line-symmetrical with respect to a center of a length along the moving direction of the operating member (11). The first and second lock portions (25, 26) lock and hold the operating member (11) selected to move along the first movement path respectively at the initial position and the connection position and lock and hold the operating member (11) selected to move along the second movement path respectively at the connection position and the initial position.

CONNECTOR WITH AN OPERATING MEMBER MOUNTABLE IN EITHER OF TWO OPPOSITE ORIENTATIONS AND LOCKS FOR LOCKING THE OPERATING MEMBER AT AN INITIAL POSITION AND A CONNECTION POSITION IN EITHER ORIENTATION

BACKGROUND

1. Field of the Invention

The invention relates to a connector.

2. Description of the Related Art

Japanese Unexamined Patent Publication No. 2003-151682 discloses a connector with male and female housings that are connectable to each other, and a slider movably mounted on the female housing. The slider includes a coupling plate and two sliding plates to define a U-shape. The sliding plate has a cam groove. The male housing includes a receptacle, and follower pins stand on outer surfaces of the receptacle. The female housing includes a tower, a skirt arranged on the outer periphery of the tower, and covers arranged at upper and lower sides of the skirt. Insertion paths are provided between the covers and the skirt for receiving the sliding plates of the slider.

Prior to the connection of the housings, the sliding plates are inserted laterally into the insertion paths and the slider is held at a retracted position. Subsequently, the receptacle is fit shallowly between the skirt and the tower of the female housing so that the follower pins enter the entrances of the cam grooves. The slider then is pushed toward an advanced position. Thus, the follower pins slide along edges of the cam grooves, and a cam mechanism acts between the slider and the male housing so that a connecting operation of the housings proceeds. The housings are connected properly when the slider reaches the advanced position and the follower pins reach ends of the cam grooves.

The slider moves from one lateral side (right side as shown) toward the other lateral side (left side as shown) with respect to the female housing so that a cam mechanism is generated between the slider and the male housing. A part of the slider including the coupling plate projects a large distance toward the one lateral side of the housing when the slider is at the retracted position. Thus, a peripheral component at the one lateral side of the housing could interfere with the coupling portion of the slider, thereby affecting the ability to use this design.

It is possible to use a connector with a slider that is oriented oppositely with respect to the female housing to achieve the cam mechanism. Further, the connector could be designed so that the slider is selectively movable in either of two opposite moving directions and to be mounted replaceably on the housing for movement in a selected one of these two directions. This enables components to be shared and enhances versatility. However, a connector that enables a slider to be mounted replaceably and reversibly on the housing can be very complicated in view of the need to have locking means for keeping the slider at the retracted position and at a standby position for each optional mounting orientation. More particularly, covers are present outside the slider, and a mold removal structure of a mold for molding the locking means may become complicated and difficult. In a worst case, there is a problem of being unable to provide the locking means.

The invention was completed based on the above situation and aims to simplify the structure of locking means while

2

enabling an operating member linearly movable with respect to a housing to be selectively mounted in directions opposite to each other.

SUMMARY

The invention relates to a connector with a housing connectable to a mating housing. The connector has an operating member that is movable linearly from an initial position to a connection position along the housing. The operating member is configured to generate a cam action with respect to the mating housing for urging the housing and the mating housing together or apart in response to movement of the operating member. A moving direction of the operating member from an initial position toward a connection position with respect to the housing is selectable from directions along a first movement path and a second movement path that are opposite to each other. The housing includes a first lock and a second lock at positions line-symmetrical with respect to a center of a length along the moving direction of the operating member. The first lock locks and holds the operating member at the initial position and the second lock locks and holds the operating member at the connection position when the operating member is moved along the first movement path. Alternatively, the second lock locks and holds the operating member at the initial position and the first lock locks and holds the operating member at the connection position when the operating member is moved along the second movement path.

The first or second movement path for the operating member is selected based on an installation situation and the like so that utility of the connector can be enhanced.

Locking the operating member at the initial position and the connection position is achieved by the first and second locks regardless of the mounting orientation. Thus, the locks need not be doubled as in the above-described prior art, and thus the structure can be simplified.

Note that an operating member of an embodiment to be described later has an assembled position beside the initial position and the connection position. However, in the case of the invention, the operating member may not have the assembled position.

The operating member may include a long groove that extends linearly in the moving direction of the operating member. The housing may include a support shaft in the center of the length along the moving direction of the operating member. The support shaft may be inserted into the long groove and may slide in contact with the long groove while being displaced with respect to the long groove during the movement of the operating member. According to this configuration, a movement of the operating member is guided by engagement of the long groove and the support shaft. Thus, unlike the prior art, covers are not required to cover the operating member from outside, and a mold removal structure need not be complicated when the first and second locks are molded on an outer surface of the housing.

The first and second locks may be resilient locks that lock an edge of the long groove. According to this configuration, the long groove performs functions of guiding a movement of the operating member and restricting the movement of the operating member. Thus, the structure can be simplified as compared to the case where separate parts are provided for these two functions.

The first and second lock portions may be resilient locks and deflectable and deformable toward a space portion provided in the housing, and the mating housing may include a prying preventing protrusion which interferes with

a wall surface of the housing to restrict the connecting operation when the mating housing is improperly connected in an oblique orientation with respect to the housing while entering the space portion and being arranged side by side with the resilient locks and capable of restricting the deflection of the resilient locks when the mating housing is properly connected to the housing. According to this configuration, since the space portion provided in the housing is effectively utilized as an entrance space for the prying preventing protrusion, the space portion needs not become a dead space. Further, since the prying preventing protrusion has both a function of preventing prying connection of the both housings and a function of restricting inadvertent deflection of the resilient locks, it is not necessary to provide a dedicated structural part for each function and a structure can be simplified.

A pair of the prying preventing protrusions may be provided on both side parts of the mating housing in a long side direction to correspond to the first and second lock portions. If the pair of prying preventing protrusions are provided on the both side parts of the mating housing in the long side direction in this way, even if the mating housing is in an arbitrary oblique orientation when the both housings are improperly connected, the connecting operation can be effectively restricted and reliability in preventing prying connection can be enhanced.

BRIEF DESCRIPTION OF DRAWINGS

FIG. 1 is a plan view of a connector of one embodiment of the present invention showing a state where an operating member is arranged at an assembled position with respect to a housing.

FIG. 2 is a plan view showing a state where the operating member is arranged at an initial position with respect to the housing and facing a mating housing.

FIG. 3 is a section along X-X of FIG. 2.

FIG. 4 is a side view showing the state where the operating member is arranged at the initial position with respect to the housing.

FIG. 5 is a section along Y-Y of FIG. 4.

FIG. 6 is a view, corresponding to FIG. 5, showing a state where the mating housing is shallowly connected and a resilient piece and a lock receiving portion are unlocked by an unlocking portion of the mating housing.

FIG. 7 is a view, corresponding to FIG. 5, showing a state where the operating member is arranged at a connection position with respect to the housing.

FIG. 8 is a plan view showing the state where the operating member is arranged at the connection position with respect to the housing.

FIG. 9 is a plan view showing a state where the operating member is arranged at the initial position in an orientation opposite to that in FIG. 2 with respect to the housing.

FIG. 10 is a plan view showing a state where the operating member is arranged at the connection position in an orientation opposite to that in FIG. 8 with respect to the housing.

FIG. 11 is a plan view of the housing.

FIG. 12 is a bottom view of the housing.

FIG. 13 is a front view of the housing.

FIG. 14 is a plan view of the operating member.

FIG. 15 is a side view of the operating member.

FIG. 16 is a section along Z-Z of FIG. 15.

FIG. 17 is a plan view of a housing in a connector of a second embodiment.

FIG. 18 is a front view of the housing in the connector of the second embodiment.

FIG. 19 is a back view of the housing in the connector of the second embodiment.

FIG. 20 is a plan view of the connector of the second embodiment showing a state where an operating member is arranged at an initial position with respect to the housing.

FIG. 21 is a plan view of the connector of the second embodiment showing a state where the operating member is arranged at a connection position with respect to the housing.

FIG. 22 is a back view of the connector of the second embodiment showing the state where the operating member is arranged at the initial position with respect to the housing.

FIG. 23 is a front view of a mating housing in the connector of the second embodiment.

FIG. 24 is a side view in section showing a state where the both housings are properly connected in the connector of the second embodiment.

DETAILED DESCRIPTION

A first embodiment of the invention is described with reference to FIGS. 1 to 16. A connector of this first embodiment includes a housing 10 and an operating member 11. The housing 10 is connectable to a mating housing 12. Note that, in the following description, surfaces of the housings 10, 12 facing each other at the start of connection are referred to as front ends concerning a front-rear direction. A vertical direction is based on FIG. 13 and a side in front of the plane of FIG. 1 is an upper side. Further, a lateral direction is based on FIG. 1.

The mating housing 12 is made of synthetic resin and includes a rectangular tubular receptacle 13 that is long and narrow in the lateral direction, as shown in FIG. 2. Cylindrical cam followers 14 project on laterally central parts of inner surfaces of upper and lower walls. A rib-like unlocking portion 15 is provided on one lateral end part of the inner surface of each of the upper and lower walls and extends in the front-rear direction. Tabs of unillustrated male terminal fittings project in the receptacle 13.

The housing 10 is made of synthetic resin and includes a rectangular block-shaped housing body 16, as shown in FIGS. 11 to 13. The housing body 16 is a long in the lateral direction and can fit in the receptacle 13. Cavities 17 penetrate through the housing body 16 in the front-rear direction, as shown in FIG. 13. The cavities 17 are arranged side by side in a width direction in upper and lower stages, and unillustrated female terminal fittings are inserted and held therein. The female terminal fitting is crimped and connected to an end part of an unillustrated wire and is connected conductively to the mating male terminal fitting when the housings 10, 12 are connected properly.

Cylindrical support shafts 18 project in laterally central parts of upper and lower surfaces (surfaces along a long side direction) of the housing body 16. Each support shaft 18 includes jaws 19 that protrude radially from a tip area of a cylindrical part. The jaws 19 are on the tip area of the cylindrical part while being spaced apart in a circumferential direction. Specifically, the jaws 19 are rectangular in a plan view and are arranged at intervals of 90° to the front, rear, left and right of the tip part of the cylindrical part.

As shown in FIG. 13, a flat laterally-extending space 21 penetrates in the front-rear direction through an upper end part of the housing body 16 above the respective cavities 17, and a flat plate-like thin wall 22 extends laterally to close an upper side of the space 21. The interior of the space 21 is divided by separation walls 23 on left and right sides.

As shown in FIG. 11, cutout grooves 24 are provided on left and right end parts of the thin wall 22. The grooves 24 extend in the front-rear direction and open on a rear end while communicating with the space 21. An inner edge part of each cutout groove 24 is continuous with a surface of the separation wall 23. Plate pieces are provided inside the grooves 24 on left and right ends of the thin wall 22 and are cantilevered rearward from front ends to define resilient locks 25, 26 that are deflectable and deformable in the vertical direction with the front ends serving as supports.

As described later, the resilient locks 25, 26 function to lock and hold the operating member 11 on the housing 10 in a movement restricted state, and are composed of a first lock 25 (right side of FIG. 11) and a second lock 26 (left side of FIG. 11). The first and second locks 25, 26 are line-symmetrically shaped and are at line-symmetrical positions across a laterally central part of the housing body 16 where the support shafts 18 are located. Note that, in the following description, unless it is particularly necessary to distinguish the first and second locks 25, 26, the first and second locks 25, 26 are referred to collectively as the resilient locks 25, 26.

As shown in FIG. 11, rear ends of the plate pieces of the resilient locks 25, 26 are retracted forward from the rear end of the housing 10. Lock projections 27 project up on rear tip parts of the plate pieces of the resilient locks 25, 26. Each lock projection 27 is circular in a plan view and has tapered slopes 28 inclined up toward a tip in a projecting direction on rear, left and right surfaces. The lock projections 27 are arranged laterally side by side at the same position as the support shafts 18 in the front-rear direction.

As shown in FIG. 13, excessive deflection restricting pieces 29 are provided on the tip parts of the plate pieces of the resilient locks 25, 26 and project down in the space 21. The excessive deflection restricting piece 29 is composed of a vertical part hanging down from the plate piece and a horizontal part bent at a right angle from the lower end of the vertical part toward the separation wall 23 to define an L-shaped in a front view.

An excessive deflection restriction receiving piece 31 projects above the horizontal part of the excessive deflection restricting piece 29 on the surface of the separation wall 23. The excessive deflection restriction receiving piece 31 is at a predetermined distance from and in parallel to the excessive deflection restricting piece 29. The resilient lock 25, 26 is deflected and deformed up and the excessive deflection restricting piece 29 comes into contact with the excessive deflection restriction receiving piece 31 from below, thereby restricting any further deflection of the resilient lock 25, 26. Thus, even if the resilient lock 25, 26 is caught by external matter, such as a looped wire, it is possible to avoid a situation where the resilient lock 25, 26 is turned out and broken. Note that, as shown in FIG. 11, a side edge part of a tip part of the resilient lock 25, 26 on the side of the separation wall 23 is cut due to the molding of the excessive deflection restriction receiving piece 31.

As shown in FIG. 13, a lock receiving portion 32 is provided on one lateral end of both upper and lower surfaces of the housing body 16. Two of the lock receiving portions 32 are point-symmetrically shaped and are arranged at point-symmetrical positions with respect to an axial center when the housing body 16 is viewed from the front. As shown in FIG. 11, each lock receiving portion 32 includes a rib-like part extending in the front-rear direction and is in front of and laterally to the resilient locks 25, 26 (right side of FIG. 11). A space into which the unlocking portion 15 of

the mating housing 12 is inserted when the housings 10, 12 are connected is secured laterally to the lock receiving portion 32.

As shown in FIGS. 11 to 13, the lock receiving portion 32 has a receiving piece 33 bent to protrude rearward and laterally on a rear end of a tip of the rib-like part in a projecting direction. As shown in FIG. 4, an insertion recess 34 is defined between the receiving piece 33 and the rib-like part and receives a locking projection 49 of the operating member 11.

As shown in FIG. 13, stoppers 35 in the form of plate pieces extending in the front-rear direction are provided on the other lateral end part of each of the upper and lower surfaces of the housing body 16. The stoppers 35 are point-symmetrically shaped at point-symmetrical positions with respect to the center of the housing body 16. Additionally, the stoppers 35 are longer in the front-rear direction than the lock receiving portions 32 and are arranged on side surfaces of the housing body 16, as shown in FIG. 11. The rear end of the stopper 35 protrudes vertically and is arranged perpendicularly, as shown in FIG. 4. When the operating member 11 reaches an initial position, to be described later, the operating member 11 can be stopped in contact with the stopper 35.

The operating member 11 is made of synthetic resin, includes a coupling 36 and two arms 37 that project parallel to each other from ends of the coupling 36 to define a U-shape, as shown in FIG. 15. The operating member 11 is successively displaceable, with respect to the housing 10, to an assembled position (see FIG. 1) where the arms 37 project obliquely rearward at an angle of inclination of about 45° with respect to the front-rear direction and the lateral direction, the initial position (see FIG. 2) where the arms 37 project laterally of the housing 10 along the lateral direction and a connection position (see FIG. 8) where the arms 37 project slightly laterally of the housing 10 along the lateral direction or are arranged substantially without projecting.

The operating member 11 includes a rotating mechanism configured to rotationally displace the operating member 11 from the assembled position to the initial position with respect to the housing 10 to gradually increase a laterally projecting amount toward the initial position and a sliding mechanism configured to linearly move and displace the operating member 11 in the lateral direction along the housing 10 from the initial position to the connection position to gradually decrease the laterally projecting amount toward the connection position. Further, a movement path of the operating member 11 can be selected from a first movement path (see an arrow A of FIG. 2) along which the operating member 11 moves from the side of the first lock 25 toward the side of the second lock 26 and a second movement path (see an arrow B of FIG. 9) along which the operating member 11 vertically inverted from a moving posture along the first movement path moves from the side of the second lock 26 toward the side of the first lock 25 when the operating member 11 is moved toward the connection position by the sliding mechanism.

The coupling 36 is a plate piece extending in the vertical direction and an operator can grip the coupling portion 36 by the fingers.

As shown in FIG. 14, a side of each of the arms 37 distant from the coupling portion 36 defines a body in the form of a flat plate expanded in the front-rear direction, and a cam groove 38 is provided in the body. The cam groove 38 is a curved bottomed groove formed by recessing an outer surface of the body of the arm 37 that is open on the front end edge of the body. The cam groove 38 is engaged with the

cam follower 14 of the mating housing 12 to generate the connecting operation of the housings 10, 12 when the operating member 11 moves between the initial position and the connection position.

A linearly extending long groove 39 is provided in an area of the body of each of the arms 37 behind the cam groove 38. The long groove 39 penetrates through the arm 37 in a plate thickness direction and is arranged along the lateral direction when the operating member 11 is at the initial position and the connection position. The support shaft 18 is inserted into the long groove 39 and slides in contact with an engaging edge 44 of the long groove 39 to guide a moving operation of the operating member 11 when the operating member 11 moves between the initial position and the connection position.

The long groove 39 receives the support shaft 18 at an end 41 distant from the coupling 36 (see FIG. 1) and can slide in contact with the support shaft 18 in an extending portion 42 linearly extending from the end 41 toward the coupling 36. The engaging edge 44 is provided on an inner part (part on the side of the housing body 16) of the edge of the long groove 39 in the plate thickness direction of the arm 37 and protrudes over the entire periphery except at escaping recesses 45 to be described later. As shown in FIG. 8, the engaging edge 44 protrudes slightly less than the jaws 19 of the support shaft 18. This engaging edge 44 slides in contact with the jaws 19 of the support shaft 18 inserted into the long groove 39 from inside except at the initial position and acts to restrict outward expanding opening deformation of the arm 37.

As shown in FIGS. 1 and 14, the end portion 41 of the long groove 39 is provided with the escaping recesses 45 by partially cutting off the engaging edge 44. The escaping recesses 45 have such a rectangular or triangular cross-sectional shape that the jaws 19 can fit inside. When the operating member 11 is at the assembled position and the arms 37 are oriented to be obliquely inclined at 45°, the escaping recesses 45 are open at intervals of 90° on front, rear, left and right sides of the engaging edge 44.

As shown in FIG. 1, the guide groove 46 is provided on the inner surface of the body of each of the arm portions 37 and is shallower than the cam groove 38. The lock projection 27 of the resilient lock 25, 26 is inserted into the guide groove 46 and slides in contact with the guide groove 46 when the operating member 11 is rotated between the assembled position and the initial position. The guide groove 46 is curved along an arc centered on a center of rotation of the operating member 11.

A bottomed escaping groove 47 is provided in an inner surface of a plate piece that connects the body and the coupling 36 in each of the arms 37. The escaping groove 47 is at the same position as the long groove 39 in the front-rear direction, extends laterally and is open on the front edge of the plate piece of the arm 37. The lock projection 27 of the resilient lock 25, 26 is inserted into the escaping groove 47 to escape when the operating member 11 moves between the initial position and the connection position.

A resilient piece 48 is provided on one 37 of the arms 37 projecting laterally (toward a side where the coupling 36 is located) along a plate surface of the arm 37 from an outer edge of the body. The resilient piece 48 is in the form of a beam supported on both ends coupled to the body of the arm 37, thinner than the body of the arm 37 and is curved into a U shape. The claw-like locking projection 49 projects forward on a tip part (U-shaped central part) of the resilient piece 48 in a projecting direction.

Next, functions of the connector are described.

The operating member 11 can be transported to a connector connecting operation site in a state where the operating member 11 and the housing 10 are separated without the operating member 11 being mounted on the housing 10.

5 At the connecting operation site, the female terminal fittings are inserted into the cavities 17 of the housing 10 and, subsequently, the operating member 11 is assembled with the housing 10 at the assembled position (see FIG. 1). In assembling, the operating member 11 is pushed to straddle 10 the housing 10 from an oblique rear side. Then, after the both arms 37 are expanded, the escaping recesses 45 of the long grooves 39 pass through the jaws 19 of the support shafts 18 and the support shafts 18 are fit into the ends 41 of the long grooves 39.

15 When the operating member 11 reaches the assembled position, the lock projection 27 of the first lock 25 is inserted into the guide groove 46 of the arm 37. At this time, the lock projection 27 contacts a front end part of the guide groove 46, thereby restricting a rotational displacement of the 20 operating member 11 in a direction opposite to that toward the initial position (see FIG. 1). Note that the operator can continuously perform a series of operations while gripping the coupling 36 of the operating member 11.

Subsequently, the operating member 11 is rotated clockwise in FIG. 1 from the assembled position toward the initial position about the support shafts 18 inserted into the ends 41 of the long grooves 39. While the operating member 11 is rotated, the rear slope 28 of the lock projection 27 slides in contact with the back surface of the guide groove 36 and the 30 first lock 25 is deflected and deformed. Large resistance is not applied to the operating member 11 from the side of the housing 10. Further, as the operating member 11 is rotated from the assembled position toward the initial position, the engaging edges 44 of the long grooves 39 slide in contact with the jaws 19 of the support shafts 18 from inside, thereby 35 restricting the detachment of the arms 37 from the support shafts 18.

When the operating member 11 reaches the initial position, the first lock 25 is displaced resiliently in a return 40 direction and the lock projection 27 is inserted into the other end 43 of the long groove 39 from the guide groove 46 (see FIG. 3). The engaging edge 44 of the long groove 39 contacts the lock projection 27 from the front, thereby 45 restricting the rotation of the operating member 11 in the return direction toward the assembled position. Further, the plate piece of the arm 37 on the other side (side where the resilient piece 48 is not provided) is stopped in contact with the rear end of the stopper 35, thereby restricting rotation of the operating member 11 beyond the initial position (see FIG. 4).

Further, when the operating member 11 reaches the initial position, the locking projection 49 of the resilient piece 48 is arranged to come laterally into contact with the rear end of the rib-like part of the lock receiving portion 32, thereby 55 restricting a movement of the operating member 11 from the initial position toward the connection position (see FIG. 5). At this time, the locking projection 49 of the resilient piece 48 is inserted into the insertion recess 34 at an inner side of the receiving piece 33 (see FIG. 4). In this way, the receiving piece 33 protects the locking projection 49 so that external matter cannot interfere with the locking projection 49 to inadvertently unlock the locking projection 49 from the lock receiving portion 32. Further, the support shafts 18 are kept inserted in the ends 41 of the long grooves 39 and are arranged to contact the ends 41 at the initial position. Thus, 60 a movement of the operating member 11 away from the connection position also is restricted (see FIG. 2).

In the above state, the receptacle 13 of the mating housing 12 is fit shallowly to the housing 10 so that the cam followers 14 enter the cam grooves 38 (see FIG. 6). Further, the unlocking portion 15 presses the tip part of the resilient piece 48 in the projecting direction and deflects the resilient piece 48 to incline rearward while extending along a plate surface direction of the arm 37. In this way, the locking projection 49 is separated from the rib-like part of the receiving piece 32 to unlock the resilient piece 48 and the receiving piece 32 from each other and to enable the operating member 11 to be displaced to the connection position. Further, deflecting and deforming the resilient piece 48 along the inner surface of the receiving piece 33 avoids interference of the resilient piece 48 and the receiving piece 33.

Subsequently, the operating member 11 is moved linearly toward the connection position (side where the second lock 26 is located) along the first movement path. In an initial stage of the movement of the operating member 11 toward the connection position, the arm 37 slides on the lateral slope 28 of the lock projection 27 and the first lock 25 is deflected and deformed inward. When the operating member 11 is moved farther toward the connection position, the lock projection 27 enters the escaping groove 47 and escapes so that the first lock 25 returns resiliently to a natural state.

In the process of moving the operating member 11 along the first movement path, the support shafts 18 are displaced relative to the long grooves 39 in a direction away from the ends 41 and the jaws 19 at the front, and rear sides of the support shafts 18 slide in contact with the engaging edges 44 of the long grooves 39 from outside, thereby guiding a movement of the operating member 11. Further, in the process of moving the operating member 11, the cam followers 14 of the mating housing 12 slide in contact with the edges of the cam grooves 38, a cam mechanism acts between the operating member 11 and the mating housing 12 and the connecting operation of the housings 10, 12 proceeds with a low connecting force. During this time, the arms 37 of the operating member 11 may expand and deform out and away from the outer surfaces of the housing body 16 by receiving connection resistance. However, the engaging edges 44 of the long grooves 39 of this embodiment contact the front and rear jaws 19 from inside, thereby restricting expanding movements of the arms 37. As a result, the arms 37 cannot expand and detach from the housing 10.

In a stage immediately before the operating member 11 reaches the connection position, the tip of the arm 37 in a moving direction slides on the lateral slope 28 of the lock projection 27 of the second lock 26 and the second lock 26 deflects inward. When the operating member 11 reaches the connection position, the second lock 26 resiliently displaces in a return direction and the lock projection 27 is inserted into the end portion 41 of the long groove 39 from inside (see FIG. 8). At this time, the lock projection 27 contacts the end 41 of the long groove 39 in the lateral direction (moving direction along the first movement path), thereby restricting a movement of the operating member 11 in the return direction toward the initial position. Further, when the operating member 11 reaches the connection position, the support shafts 18 are arranged to contact the other end portions 43 of the long grooves 39 and the coupling 36 is arranged to contact the side surface of the housing 10, thereby restricting any further movement of the operating member 11 beyond the connection position. Furthermore, the lock projection 27 of the second lock 26 is arranged in the end 41 of the long groove 39 and the support shaft 18 is arranged in the other end 43 of the long groove 39, thereby restricting a rotational displacement of the operating mem-

ber 11. At the connection position, the cam followers 14 are in final end parts of the cam grooves 38 and the housings 10, 12 are connected properly.

A situation may arise in which the operating member 11 cannot be moved along the first movement path due to an interfering object, such as a peripheral component, lateral to (right side of FIG. 2) the housing 10, and the coupling 36 or the like of the operating member 11 at the initial position may interfere with the interfering object. In this situation, the operating member 11 can be moved along the second movement path opposite to the first movement path.

In this case, the operating member 11 is inverted vertically and the coupling 36 is arranged to be on a side (left side of FIG. 9) opposite to that when the operating member 11 is moved along the first movement path with respect to the housing 10. First, the operating member 11 is assembled at the assembled position. At the assembled position, the lock projection 27 of the second lock 26 is inserted into the guide groove 46 of the arm 37 and contacts the front end of the guide groove 46 to restrict rotation of the operating member 11 in the direction opposite to that toward the initial position.

Subsequently, the operating member 11 is rotated in a counterclockwise direction about the support shafts 18 from the assembled position toward the initial position. When the operating member 11 reaches the initial position, the lock projection 27 of the second lock 26 is inserted resiliently into the other end 43 of the long groove 39 from inside and the engaging edge 44 of the long groove 39 contacts the lock projection 27 from the front, thereby restricting a return displacement of the operating member 11 to the assembled position. Further, the plate piece of the arm 37 on the other side (where the resilient piece 48 is not provided) is stopped in contact with the rear end of the stopper 35, thereby restricting further rotation of the operating member 11 beyond the initial position (see FIG. 9). Furthermore, the locking projection 49 of the resilient piece 48 locks the lock receiving portion 32 to restrict movement of the operating member 11 to the connection position. In this case, the locking projection 49 locks the lock receiving portion 32 on the lower surface (surface where the resilient locks 25, 26 are not provided) of the housing 10 on a side opposite to that when the first movement path is selected. Further, the stopper 35 to be stopped in contact with the arm 37 at the initial position is provided on the lower surface of the housing 10 when the first movement path is selected while being provided on the upper surface of the housing 10 when the second movement path is selected.

Subsequently, the housings 10, 12 are connected shallowly and the cam followers 14 enter the cam grooves 38. Then, the resilient piece 48 is pressed by the unlocking portion 15 and deflected and deformed rearward to move away from the lock receiving portion 32, thereby enabling the operating member 11 to be moved to the connection position. Subsequently, the operating member 11 is moved linearly toward the connection position (side where the first lock 25 is located) along the second movement path. When the operating member 11 reaches the connection position, the lock projection 27 of the first lock 25 is inserted resiliently into the end 41 of the long groove 39 from inside, and the end 41 of the long groove 39 contacts the lock projection 27 in a return direction to the initial position, thereby restricting a return movement of the operating member 11 to the initial position (see FIG. 10). Further, the lock projection 27 of the second lock 26 is inserted into the escaping groove 47 of the arm 37 and allowed to escape.

As just described, locking functions of the first and second locks 25, 26 at each of the initial position and the connection

11

position are alternated when the operating member 11 is moved along the first movement path and when the operating member 11 is moved along the second movement path, but the locking functions themselves are the same.

Each of the following effects can be achieved by this embodiment.

The operating member 11 is rotated from the assembled position to the initial position and the laterally projecting amount of the housing 10 is suppressed more at the assembled position than at the initial position. Thus, the operating member 11 is less likely to interfere with external matter intruding to a lateral side of the housing 10 at the assembled position. On the other hand, since a transition is made from the rotating operation by the rotating mechanism to the linearly moving operation by the sliding mechanism at the initial position, the operating member 11 does not stay long at the initial position and is less likely to interfere with external matter also at the initial position. As a result, the operating member 11 is not likely to be moved inadvertently from the initial position to the connection position or broken due to interference with external matter.

Further, the arms 37 of the operating member 11 are not covered from outside by members such as conventional covers, but the expanding movements are suppressed by the contact of the engaging edges 44 of the long grooves 39 with the jaws 19 of the support shafts 18 to prevent detachment from the housing 10. Omitting the conventional covers avoids enlargement of the housing 10. This is ensured by arranging the operating member 11 exposed on the outer surfaces without being covered by the housing 10.

Further, the operating member 11 is moved linearly from the initial position to the connection position and either one of the first and second movement paths can be selected as the movement path to the connection position. Thus, the movement path of the operating member 11 can be determined depending on an installation situation and usefulness is enhanced. In addition, the locking means for keeping the operating member 11 at the initial position and the connection position are realized by the first lock 25 and the second lock 26 and four locking means corresponding to each movement path and each position are not provided. Thus, a structure can be simplified. In this case, members such as the conventional covers to cover the operating member 11 are not present on the outer surfaces of the housing 10. Therefore, a mold removal structure to mold the first and second locks 25, 26 on the outer surface of the housing 10 need not be complicated.

The engaging edges 44 of the long grooves 39 slide in contact with the support shafts 18 to guide a movement of the operating member 11. The long grooves 39 linearly guide a movement of the operating member 11, restrict a movement of the operating member 11 by being locked by the resilient locks 25, 26, and suppress opening deformation of the operating member 11 by causing the jaws 19 of the support shafts 18 to contact the engaging edges 44. Thus, as compared to the case where each function is provided individually, the structure of the operating member 11 can be simplified.

The resilient lock 25, 26 restricts a displacement of the operating member 11 in the direction opposite to that from the assembled position toward the initial position by locking the lock projection 27 to the front end part of the guide groove 46 when the operating member 11 is at the assembled position and restricts a displacement of the operating member 11 in the return direction from the initial position to the assembled position by locking the lock projection 27 to the other end 43 of the long groove 39 when the operating

12

member 11 is at the initial position. Thus, the operating member 11 is locked and held to the resilient lock 25, 26 both at the initial position and at the assembled position and it is not necessary to provide the locking structure for each of the initial position and the assembled position so that the structure can be more simplified.

The unlocking portion 15 of the mating housing 12 presses the resilient piece 48 when the operating member 11 is at the initial position. Thus, the resilient piece 48 is deflected along the plate surface of the arm 37 to be unlocked from the lock receiving portion 32 and the operating member 11 can displace toward the connection position. In this case, a locking margin of the resilient piece 48 to the lock receiving portion 32 is determined in the direction along the plate surface of the arm 37, freedom in setting the locking margin is high and a sufficiently large locking margin can be set. As a result, the locking strength of the operating member 11 at the initial position can be enhanced.

Further, the resilient piece 48 is a beam supported on both ends coupled to the body of the arm 37, external matter such as a looped wire is less likely to be caught by the arm 37 and the deflection strength of the arm 37 can be enhanced.

Further, since the lock receiving portions 32 to be locked by the resilient piece 48 are provided on the outer surfaces of the housing 10 and members such as the conventional covers are not present on the outer surfaces of the housing 10, a mold removal structure in molding the lock receiving portions 32 needs not be complicated.

FIGS. 17 to 24 show a second embodiment of the present invention. The second embodiment differs from the first embodiment in partial structures of a housing 10A and an operating member 11A, but has a basic structure common to the first embodiment. Further, a structure of a mating housing 12 is embodied. Note that, in the following description, parts identical or equivalent to those of the first embodiment are denoted by the same reference signs or the same reference signs with A at the end and repeated description is omitted.

A receptacle 13 of a mating housing 12 includes a back wall 51 substantially extending along a vertical direction and a lateral direction as shown in FIG. 23. A plurality of mating male terminal fittings 52 are mounted through the back wall 51. As shown in FIG. 24, each male terminal fitting 52 is long and narrow and bent into an L shape in a side view, and includes a terminal connecting portion 53 extending in a front-rear direction and penetrating through the back wall 51 and a board connecting portion 54 extending in the vertical direction and to be connected to a connection hole of an unillustrated circuit board. As just described, the mating housing 12 is to be mounted on the circuit board.

Further, as shown in FIG. 23, the receptacle 13 is provided with a pair of prying preventing protrusions 55 projecting forward from positions near an upper end on both left and right side parts of the back wall 51. The prying preventing protrusions 55 are arranged on both sides across cam followers 14 and side by side with large-size male terminal fittings 52 between the male terminal fittings 52 arranged in an upper stage. Further, each of the prying preventing protrusions 55 is in the form of a flat plate piece extending in the lateral direction and includes, as shown in FIG. 24, a straight portion 56 arranged along a front-rear direction from the back wall 51 to an intermediate position in the front-rear direction in a rear upper surface part and an inclined portion 57 inclined gradually downwardly to the front from the intermediate position in the front-rear direction to a front end part in a front upper surface part. A laterally central part of each of the both prying preventing protrusions 55

includes a lightening groove 58 in a lower surface, which groove extends in the front-rear direction and is open in the rear surface of the back wall 51. By including the lightening groove 58, the prying preventing protrusion 55 is formed to have a substantially constant thickness from the straight portion 56 to the inclined portion 57. The front ends (tips) of the both prying preventing protrusions 55 are arranged to project further forward than the front ends of the respective male terminal fittings 52 in the receptacle 13. As shown in FIG. 23, the mating housing 12 is line-symmetrically formed with a lateral center, where a pair of upper and lower cam followers 14 are located, serving as an axis of symmetry.

As shown in FIG. 18, the housing 10A is also line-symmetrically shaped with a lateral center, where a pair of upper and lower support shafts 18A are located, serving as an axis of symmetry. Parts equivalent to the lock receiving portions 32 of the first embodiment are not provided on both upper and lower surfaces of a housing body 16A. Further, jaws 19A of the support shaft 18A are provided only on both front and rear sides of a cylindrical part.

Two stoppers 35A are provided on both left and right parts of each of the upper and lower surfaces of the housing body 16A. As shown in FIG. 17, each stopper 35A is in the form of a plate extending in the front-rear direction along a side surface of the housing body 16A and includes a receiving end portion 59 bent toward a laterally central side on a rear end part. The rear surface of the receiving end portion 59 is arranged along the lateral direction and a lateral length is longer than a lateral dimension of the other part (part excluding the receiving end portion 59) of the stopper 35A.

Two cutout grooves 24A are provided at each of both left and right sides across the support shaft 18A on the upper surface of the housing body 16A. As shown in FIGS. 17 and 19, each cutout groove 24A extends in the front-rear direction while having a constant width and a constant depth and is open in the form of a slit extending in the vertical direction in the rear surface of the housing body 16A.

Resilient locks 25A, 26A are arranged between the corresponding pair of cutout grooves 24A in a first lock 25A and a second lock 26A on both left and right side parts of the housing body 16A. The resilient locks 25A, 26A define spaces 21A located therebelow. Each space 21A communicates with each cutout groove 24A and is defined also by a front part of an upper wall and an upper part of a rear wall of the housing body 16A and, as shown in FIG. 18, forms an opening having a rectangular cross-section in the front surface of the housing body 16A. The spaces 21A are arranged at positions corresponding to the prying preventing protrusions 55 of the mating housing 12 in the both left and right side parts of the housing body 16A.

As shown in FIG. 24, the resilient lock 25A, 26A is formed such that a front end is connected to the front part of the upper wall of the housing body 16A without any step and a rear end is inclined down to the rear and connected to the upper part of the rear wall of the housing body 16A. Thus, the resilient lock 25A, 26A is supported on both ends and deflectable and deformable toward the space 21A with both front and rear ends serving as supporting points of deflection, and differ from those of the first embodiment that are cantilevered. The resilient lock 25A, 26A has no excessive deflection restricting piece 29 (see FIG. 13) and no excessive deflection restriction receiving piece 31 projects into the space 21. An excessive deflection restricting structure replacing the excessive deflection restricting pieces 29 and excessive deflection restriction receiving pieces 31 is realized by the prying preventing protrusions 55 as described later.

Unlike the first embodiment, the space 21, the thin wall 22 and the separation walls 23 are not formed in a laterally central side of an upper part of the housing body 16A. In the case of the second embodiment, the spaces 21A are formed only at positions corresponding to the resilient locks 25A, 26A. As shown in FIGS. 18 and 19, large-size cavities 17B capable of accommodating unillustrated large-size female terminal fittings are provided laterally side by side at positions corresponding to the mating large-size male terminal fittings 52B in a laterally central part and both left and right end parts of the upper part of the housing body 16A. The left and right spaces 21A are arranged side by side with these large-size cavities 17B between the cavities 17B.

The operating member 11A includes two arms 37A each having a cam groove 38 and a long groove 39A as in the first embodiment, but the arm 37A is not provided with a part corresponding to the resilient piece 48 (see FIG. 2), as shown in FIG. 20. An end 41 of the long groove 39A is provided with escaping recesses 45A by cutting an engaging edge portion 44A obliquely with respect to the front-rear direction. When the operating member 11A is at an assembled position where the operating member 11A is oriented obliquely with respect to the front-rear direction, the support shafts 18A can pass through the escaping recesses 45A and be fit into the ends 41 of the long grooves 39A.

The arm 37A includes a strip having the cam groove 38 and the long groove 39A and extending in the lateral direction toward a coupling portion 36 from an expanded part expanded in the front-rear direction, and a sliding surface 61 slidable on the receiving end portion 59 of the stopper 35A extends along the lateral direction on the front end of this strip. Further, anti-slip portions 63, 64 are provided at positions near the coupling portion 36 of the strips on the outer surfaces of the arms 37A. As shown in FIG. 22, the anti-slip portions 63, 64 are composed of ribs 63 extending in the front-rear direction and multistage portions 64 adjacent to the ribs 63 from a side opposite to the coupling portion 36 and cut in a multistage manner on the outer surfaces of the arms 37A, and function as holds or slip resistance for fingers by being gripped by the fingers of an operator when the operating member 11A is moved.

Next, functions and effects of the second embodiment are described.

Prior to a connecting operation of the housings 10A, 12, the operating member 11A is held at an initial position. As shown in FIG. 20, at the initial position, a lock projection 27 of the first lock 25A is in contact with another end 43 of the long groove 39A, thereby restricting a movement of the operating member 11A toward a connection position, and the support shafts 18A are in contact with the ends 41 of the long grooves 39A, thereby restricting a movement of the operating member 11A in a direction opposite to a direction toward the connection position, as in the first embodiment.

Subsequently, the housing 10A is fit shallowly into the receptacle 13 of the mating housing 12 together with a front part of the operating member 11A. In that state, a pushing force toward the connection position is applied to the operating member 11A to unlock the other end 43 of the long groove 39A and the lock projection 27 of the first lock 25A from each other. Subsequently, the operating member 11A is slid along a first movement path toward the connection position. In the process of moving the operating member 11A toward the connection position, the support shafts 18A slide in contact with the engaging edge portions 44A of the long grooves 39A and the receiving ends 59 of the stoppers 35A slide in contact with the sliding surfaces 61 of the arms

15

37A to guide a movement of the operating member 11A. At this time, the lock projection 27 of the first lock 25A is arranged while being spaced forward of the sliding surface 61 of the arm 37A. Thus, unlike the first embodiment, the arm 37A is not provided with a part corresponding to the escaping groove 47 (see FIG. 7) for allowing the lock projection 27 to escape.

Further, in the process of moving the operating member 11A toward the connection position, the cam followers 14 slide in contact with groove surfaces of the cam grooves 38, whereby the connecting operation of the both housings 10A, 12 proceeds and the both prying preventing protrusions 55 are respectively inserted into the facing spaces 21A. Here, if the mating housing 12 is in an oblique orientation inclined from a proper connection orientation with respect to the housing 10A, the front ends of the both prying preventing protrusions 55 come into contact with the front surface of the housing body 16A to stop the connecting operation of the housings 10A, 12. This prevents the front ends of the terminal connecting portions 53 of the respective male terminal fittings 52 from coming into contact with the front surface of the housing body 16A, thereby avoiding a situation where the respective male terminal fittings 52 are fractured or broken.

Immediately before the operating member 11A reaches the connection position, the arm 37A interferes with the lock projection 27 of the second lock 26A and slides in contact with a slope 28 of the lock projection 27 and the second lock 26A is deflected and deformed toward the space 21A. At this time, the second lock 26A may interfere with the prying preventing protrusion 55 that has entered the space 21A on the side of this second lock 26A, but the inclined portion 57 located below the lock projection 27 is shaped obliquely to be retracted in a deflection direction of the second lock 26A, thereby avoiding the strong interference of the second lock 26A with the prying preventing protrusion 55.

When the operating member 11A reaches the connection position, the second lock portion 26A substantially resiliently returns and the lock projection 27 is inserted into the end 41 of the long groove 39A. As shown in FIG. 21, at the connection position, the lock projection 27 of the second lock 26A is in contact with the end 41 of the long groove 39A, thereby restricting a movement of the operating member 11A in the return direction to the initial position, and the support shafts 18A are in contact with the other ends 43 of the long grooves 39A, thereby restricting a movement of the operating member 11A beyond the connection position, as in the first embodiment. Further, at the connection position, the cam followers 14 reach final end parts of the cam grooves 38, the housings 10A, 12 are connected properly, and the male and female terminal fittings are connected properly.

The second lock 26A merely is deflected temporarily and deformed toward the space 21A while interfering with the arm 37A immediately before the operating member 11A reaches the connection position. Thus, even if the second lock 26A contacts the prying preventing protrusion 55, no particularly large sliding resistance is generated.

As shown in FIG. 24, when the operating member 11A reaches the connection position, the prying preventing protrusions 55 are arranged side by side with the resilient locks 25A, 26A (second lock 26A in the shown case) in the spaces 21A and the inclined portions 57 are separated from front end parts of the resilient locks 25A, 26A, whereas the straight portions 56 are arranged in contact with or in proximity to rear end parts of the resilient locks 25A, 26A. Thus, the resilient locks 25A, 26A are prevented by the prying preventing protrusions 55 from being largely

16

deflected and deformed toward the spaces 21A upon receiving an external force such as due to interference with external matter. As a result, the locked state of the resilient locks 25A, 26A and the long groove 39A of the operating member is maintained stably. Further, a situation where the resilient locks 25A, 26A are deflected excessively and deformed beyond a resiliency limit can be avoided. Note that, while the operating member 11A is moving along the above first movement path, the first lock 25A is held out of interference with the prying preventing protrusion 55 that has entered the space 21A on the side of this first lock 25A. Further, the operating member 11A is moved along a second movement path opposite to the above first movement path and has movements thereof restricted at the initial position and the connection position by a mechanism similar to that of the first embodiment.

As described above, according to the second embodiment, the mating housing 12 is provided with the prying preventing protrusions 55, the prying preventing protrusions 55 interfere with the wall of the housing 10A to restrict the connecting operation when the mating housing 12 is improperly connected in an oblique orientation with respect to the housing 10A, whereas the prying preventing protrusions 55 enter the spaces 21A and are arranged side by side with the resilient locks 25A, 26A and can restrict the deflection of the resilient locks 25A, 26A when the both housings 10A, 12 are connected properly. Thus, the spaces 21A provided in the housing 10A are utilized as entrance spaces for the prying preventing protrusions 55 and need not become dead spaces. Further, since the prying preventing protrusions 55 have both a function of preventing prying connection of the housings 10A, 12 and a function of restricting inadvertent deflection of the resilient locks 25A, 26A, it is not necessary to provide dedicated structural parts for each function and a structure can be simplified.

Further, a long side direction (lateral direction of FIG. 23) of the mating housing 12 is a sliding direction of the operating member 11A and an arrangement direction of the first and second locks 25A, 26A, and the prying preventing protrusions 55 are provided on the side parts of the mating housing 12 in the long side direction to correspond to the first and second locks 25A, 26A. Thus, even if the mating housing 12 is in an arbitrary oblique orientation when the housings 10A, 12 are connected improperly, the connecting operation can be restricted and reliability in preventing prying connection can be enhanced.

Other embodiments are briefly described below.

Contrary to the above first embodiment, the support shafts may be provided on the inner surfaces of the arms of the operating member, the long grooves may be provided to be open in the outer surfaces of the housing and the support shafts may be inserted into the long grooves from outside to be slidable in contact with the long grooves.

The long grooves may have a bottomed shape.

The shape and the number of the jaws provided on the support shaft are arbitrary and the escaping recesses may be provided to correspond to the jaws.

Wires connected to the female terminal fittings are pulled out rearwardly of the housing and a wire cover may be installed to cover the rear surface of the housing. The support shafts, the lock receiving portions and the resilient locks may be provided on the wire cover.

The mating housing may be provided with only one prying preventing protrusion or may be provided with three or more prying preventing protrusions. In the case of pro-

17

viding three or more prying preventing protrusions, the prying preventing protrusions may include the one that does not enter the space.

What is claimed is:

1. A connector, comprising:

a housing (10, 10A) connectable to a mating housing (12); and

an operating member (11, 11A) linearly movable between an initial position and a connection position along the housing (10, 10A) and configured to engage the mating housing (12) to generate a cam action for urging the housing (10) and the mating housing (12) toward or away from each other during a movement of the operating member (11, 11A) on the housing (10, 10A), wherein:

a moving direction of the operating member (11, 11A) from the initial position toward the connection position with respect to the housing (10, 10A) is selectable from directions along a first movement path and a second movement path opposite to each other;

the housing (10, 10A) includes a first lock (25, 25A) and a second lock (26, 26A) at positions line-symmetrical with respect to a center of a length along the moving direction of the operating member (11, 11A);

the first lock (25, 25A) locks and holds the operating member (11, 11A) at the initial position and the second lock (26, 26A) locks and holds the operating member (11, 11A) at the connection position when the operating member (11) is moved along the first movement path; and

the second lock (26) locks and holds the operating member (11, 11A) at the initial position and the first lock (25, 25A) locks and holds the operating member (11, 11A) at the connection position when the operating member (11, 11A) is moved along the second movement path.

2. The connector of claim 1, wherein:

the operating member (11, 11A) includes a long groove (39, 39A) linearly extending in the moving direction of the operating member (11, 11A);

the housing (10, 10A) includes a support shaft (18, 18A) in the center of the length along the moving direction of the operating member (11, 11A); and

the support shaft (18, 18A) is inserted into the long groove (39, 39A) and slides in contact with the long groove (39, 39A) while being relatively displaced with respect to the long groove (39, 39A) during the movement of the operating member (11, 11A).

3. The connector of claim 1, wherein the first and second locks (25, 25A, 26, 26A) are resilient locks and resiliently lock a groove edge (44, 44A) of the long groove (39, 39A).

4. The connector of claim 1, wherein:

the first and second locks (25A, 26A) are resilient locks and deflectable and deformable toward a space (21A) provided in the housing (10A); and

the mating housing (12) includes a prying preventing protrusion (55) that interferes with a wall surface of the housing (10A) to restrict the connecting operation when the mating housing (12) is connected improperly in an oblique orientation with respect to the housing (10A) while entering the space portion and being arranged side by side with the resilient locks (25A, 26A) and capable of restricting the deflection of the resilient locks (25A, 26A) when the mating housing (12) is properly connected to the housing (10A).

5. The connector of claim 4, wherein a pair of the prying preventing protrusions (55) are provided on both side parts of the mating housing (12) in a long side direction to correspond to the first and second locks (25A, 26A).
